CLAIM

The ornamental design for an epistaxis treatment device, as shown and described.

DESCRIPTION

FIG. 1 is a perspective view of a first embodiment of an epistaxis treatment device, showing my new design;

FIG. 2 is a right side view thereof, the left side view being a mirror image thereof;

FIG. 3 is a top view thereof;

FIG. 4 is a bottom view thereof;

FIG. 5 is a back view thereof;

FIG. 6 is a front view thereof;

FIG. 7 is a perspective view of a second embodiment of an epistaxis treatment device, according to the invention;

FIG. 8 is a right side view thereof, the left side view being a mirror image thereof;

FIG. 9 is a top view thereof;

FIG. 10 is a bottom view thereof;

FIG. 11 is a back view thereof; and,

FIG. 12 is a front view thereof.
